UNITED STATES PATENT OFFICE.

AUGUST ALBRECHT, OF LÜBECK, GERMANY.

SALTING APPARATUS.

1,055,504.

Specification of Letters Patent. Patented Mar. 11, 1913.

Application filed July 30, 1912. Serial No. 712,286.

To all whom it may concern:

Be it known that I, AUGUST ALBRECHT, subject of the German Empire, residing at Lübeck, Germany, have invented certain new and useful Improvements in Salting Apparatus, of which the following is a specification, reference being had therein to the accompanying drawing.

The subject of the present invention is a salting apparatus with the pickling salt surrounding the meat in an unbroken circle under the action of electricity.

As against the similar salting apparatuses already known, the invention consists in a valuable improvement of them which is distinguished by the vats, which are put in connection with one another by clay pipes, and also the pump consisting of earthenware, coated with a specially hard glazing of great resisting power, to allow of the electric current introduced into the salting vat acting equally on the meat to be treated without affecting the holder. Together with a saving in electric force, the action of which on the salting vats is completely avoided, a speedy salting of the goods is procured which is quite unobjectionable hygienically in every way, as all the parts which come in contact with the pickling salt cannot oxidize and are easily cleaned and cause no trouble.

In the illustration: Figure I. shows the subject of the invention in section, and Fig. II the view from above.

According to the invention the apparatus consists of two trough-like earthenware holders A and B. The holder A is provided with a pickling bottom a' with holes a , which is supported on a ridge l . On each of the two fronts of the holder A electrodes b and b' are fixed and each is covered with an earthenware cap d with holes d' , to prevent its coming into direct contact with the meat. Further, in the holder A, a lid c with holes c' is arranged which is placed over the piece of meat and perhaps weighted. Under the bottom a' a clay pipe e is introduced into the holder A, which is connected with the delivery pipe f of a pump m . With the suction pipe g of the pump m a clay pipe h is connected which is introduced into the holder B. In the upper part of the holder

A a clay pipe i which is introduced on the slope into the holder B, is arranged so that its inlet when the holder is full lies above lid c . Under the exit of the pipe i in the holder B a cooling coil k is arranged, in which cold water circulates.

The letter H, designates the lower part of the pump.

The goods to be treated are placed on the bottom a' of the holder A, lightly covered with the lid with holes c' and perhaps weighted or kept down by means of a suitable appliance for applying pressure. The holder B is filled with the pickling material the pump m set to work now sucks the pickling material by means of the connecting pipes g, h from the holder B and presses it by means of the connecting pipes e, f into the holder A. The material then ascends through the apertures a to the meat, presses up through the lid c to space k' and flows back through the tube i again into the holder B, via the cooling coil k , by which any possible alteration of temperature is made to disappear, and then again enters on its circuit. The electric current started at the beginning of the pickling material's circuit makes the solution of chlorid of sodium and water penetrate to the very inmost parts of the meat and the bones and as there is no loss of the current by conductible parts of the holder, etc., an exceedingly quick salting is obtained.

Any letting off of the salting material from the holder is conveniently done by loosening the tubes e and g from the pump, after which the holder, pump and tubes can be easily cleaned, as the earthenware parts are not attacked by the salt-solution nor do they allow of oxidation or rotting.

Having now described the invention and the manner of using it, what I claim and desire to secure, is—

In salting apparatus, two trough-like enameled vats, A and B, the holding vat A having a pickling bottom a' with apertures therethrough, a lid c , having apertures c' disposed on said holding vat, below the upper edge of said vat, a ridge l , supporting said bottom a' , said vat B, a force pump between said vats, a suction pipe connecting said pump with the lower part of said vat

- B, a delivery pipe connecting said pump with a space below the perforated bottom of vat A, an inclined pipe connecting the part k' , of the vat A with the upper part of vat 5 B, cooling means and means to pass an electric current through the substance being treated.

In testimony whereof I affix my signature in the presence of two witnesses.

AUGUST ALBRECHT.
